UNITED STATES PATENT OFFICE.

MILES J. VOTAVA, OF CHICAGO, ILLINOIS.

OIL BURNER.

Application filed June 28, 1924. Serial No. 722,944.

My invention relates to hydrocarbon oil burners adapted especially for household, domestic and industrial heating and refers more particularly to the gravity type of oil burners, that is the type wherein the fuel oil is fed to the burner by gravity without the aid of mechanical devices, such as pumps, blowers and the like.

The invention relates to oil burners which are adapted to be placed inside of domestic heaters such as hot water heaters, steam boilers and the like, and wherein the natural draft of the chimney connections is relied upon for drawing in a sufficient quantity of air for proper combustion with the hydrocarbon fuel utilized with the apparatus of this invention.

An object of my invention is to provide an oil burner which will burn hydrocarbon oil in the most efficient and economical manner with a flame of extremely high temperature with substantially no production of soot and under proper conditions of combustion.

Another object of the invention is to provide an oil burner having a pan into which oil is fed and which pan is heated by the combustion of the oil for vaporizing the oil as it is delivered to the pan and the provision of an air duct centrally of the pan whereby air passing therethrough under the influence of the chimney connections may cool the pan somewhat and at the same time becoming heated for accelerating combustion.

A further object of the invention is to provide an oil burner which will be highly efficient in the matter of combustion and which has no moving parts to get out of order.

A further object of the invention is to provide an oil burner of the gravity type including a plate adapted to be placed upon the grates of the heater which plate has a plurality of concentric grooves therein into which the oil is delivered for combustion purposes.

A still further object of the invention is to provide an oil burner of the gravity type including a plate adapted to be placed upon the grates of a heater which plate has a centrally disposed opening therein through which air passes, a pre-heater mounted above the opening into which pre-heater oil is fed and from which the oil is discharged onto the plate, which plate becomes

heated as the oil is burned, which heating vaporizes the oil delivered thereto. Said heat also tends to warm the oil which is within the pre-heater and also tends to heat the incoming air which is induced through said opening by the chimney connections in the heater, which burner and its attachment may be readily applied to any type of heater without disarrangement or removal of any of the parts of the heater.

A yet further object of the invention is to provide an oil burner of the gravity type which will be efficient in operation and which will permit the proper mixture of air with hydrocarbon fuel tending toward ideal combustion conditions.

The above recited and other objects of the invention will be apparent from the following description and drawings, and will be particularly pointed out in the appended claims.

Generally speaking, I carry out the preferred embodiment of my invention by providing a plate, preferably of cast iron, which is mounted on the grates of a furnace or heater, covering the grate area which is not occupied by the plate, so as to preclude the passage of air therethrough and restrict the passage of air to a centrally disposed opening in said plate. Above the plate I mount what I term a pre-heater, into which oil is fed, where it is heated by the products of combustion and from which the oil is delivered on to the plate where it is vaporized and ignited by reason of the heat of the plate and by reason of the heated zone immediately above the base of the plate.

In the accompanying drawings:

Fig. 1 is a vertical sectional view of the preferred embodiment of the invention, and

Fig. 2 is a top plan view of the embodiment shown in Fig. 1.

In the drawings I have shown a fragmentary portion of the fire pot A of a domestic heater, which fire pot is provided with the usual grate bars 5 mounted in the usual manner so as to be rocked or shaken for the purpose of removing the ashes. The sides of the fire pot A are designated at 6 and may be of any shape, size or arrangement as desired.

The invention consists of a plate 7 formed preferably of cast iron, having a lower marginal portion 8 which rests on a plate 22

which rests on the grate 5 of the heater and is fashioned with a plurality of concentric grooves of which there are three shown in the drawings, to wit, 9, 10 and 11, with the depths of the grooves varying as shown. In the drawings groove 9 is the innermost while groove 11 is the outermost, the outer wall of groove 11 being extended upwardly, terminating in an upper edge 12 which is relatively higher than any of the walls defining the several grooves which edge 12 serves as a wall to retain the fuel oil within the plate. Between the grooves 9, 10, and 11 are ridges 13 and 14, the ridge 13 being slightly higher than the ridge 14. The plate is formed with a centrally disposed opening 15 which is defined by a collar 16, the upper edge 17 of which is above the edge 12 of the plate. A short distance below the top edge 17 of the collar 16 I provide two steps or notches 18 and 19, arranged as shown. Communicating with the outer groove 11 is an outlet opening 20 which is formed by a core inserted at the time the casting is made, with which opening 20 a pipe 21 communicates for permitting whatever accumulation of oil there is in the outer groove 11 to run off in a manner hereinafter described.

In applying the plate to a heater, the grate area not occupied by the plate is preferably covered over as at 22 by a covering made of asbestos, fireclay and sand, for the purpose of preventing the passage of any air from below the grate to the chimney connections except through the centrally disposed opening 15 of the plate. In this manner I secure a supply of air which, when regulated in the manner hereinafter described, I find proper and sufficient for combination with the hydrocarbon fuel for purposes of combustion.

Above the top of the collar 16 I mount what I term a pre-heater which consists of a hollow member 23 having an imperforate top 24, a dished bottom 25 at the center of which bottom there is a threaded opening 26 with which cooperates a threaded plug 27, which plug has a centrally disposed passageway 28 therethrough with which passageway a pipe 29 communicates, the other end of which is connected, in a manner not shown, with a source of oil supply in order that the hydrocarbon oil may be supplied to the pre-heater. As will be noted the supply pipe passes upwardly through the ashpit and the grate bars to the pre-heater. A regulating valve 39 is interposed in this

supply pipe for controlling the passage of fuel to the pre-heater. The top 24 has a centrally disposed threaded opening 30 in which is inserted a screw threaded plug 31. The bottom of the pre-heater is provided with a plurality of openings 32 in which are threaded nipples 33.

These nipples are short and provide means for delivering the hydrocarbon oil from the pre-heater on to the plate. Furthermore, the nipples 33 are so positioned as to serve as supports for the pre-heater and are arranged as shown in the drawings to rest on the shoulder 18 formed about the upper end of the collar 16. The length of the nipples is such as to properly position the pre-heater with respect to the end of the collar 16 in order to control to some extent the passage of air through the opening. It will be noted that the side of the pre-heater is cast with a downwardly projecting margin 34 for the purpose of limiting, in connection with the length of the nipples 33, the maximum amount of air that may pass underneath the pre-heater from the opening 15. In order to more fully control the passage of air through the openings and underneath the pre-heater where the air is spread by reason of the formation and relation of parts, I provide a cap 35 having an inturned upper marginal portion 36, so that the cap may be applied over the top of the pre-heater. The upper part of the cap is cut away so that the same will fit snugly over the top of the pre-heater. The side portion of the cap is adapted to extend downwardly toward the top edge 17 of the collar 16 for varying the air passageway. The cap may be adjusted in vertical position by inserting a washer 38, shim or the like between the marginal flange 36 and the top surface of the pre-heater and in this way secure the cap in any desired vertical position. This adjustment is necessary in order that a burner may be adapted to the draft conditions of any type of heating plant into which it may be put in service. For facilitating removal of the cap I provide outstanding lugs 37 at diametrically opposite points, in order to grasp the cap by a tool, poker, or the like. The supply pipe 29 may be connected to any suitable source of supply such as a gravity tank or any other source. The outlet pipe 21 from the groove 11 of the plate may be directed to cooperate with a trip valve for automatically shutting off the supply of oil through the pipe 29 when the groove 11 is filled to a height which will discharge through the outlet pipe 21, which sometimes happens when proper ignition does not take place. Whenever ignition is insufficient or absent, unless the oil supply is stopped, the oil would overflow on to the floor surrounding the heating plant.

As will be noted from the drawings, the underside of the plate is cast with corrugations therein so that the contour of the underside of the plate is somewhat similar to the upper surface of the same. This is made so in order that the incoming air which passes upwardly through the grate bars and

through the opening 15 in the plate will tend to cool the plate to a greater degree than would happen if the underside of the plate were perfectly smooth.

6 The operation of the device is as follows: The grate area being covered to preclude the passageway of air anywhere except through the opening 15 in the plate results in the flow of air from the ash pit upward-
 10 ly under influence of the chimney connections through the opening 15 in the plate. As the air moves under the chimney or induced draft it strikes against the under side of the plate and then is reduced in
 15 volume to pass through the opening 15 where it strikes the under side of the pre-heater. Here by reason of the formation of the under side of the heater the air is deflected outwardly in a ring and down-
 20 wardly by reason of the cap 35 and spreads in a sheet immediately above the surface of the plate. Hydrocarbon oil is admitted through the plate 29 into the pre-heater where the dished portion of the bottom is
 25 filled and then any excess amount of oil tends to overflow through the nipples 33 onto the shoulder 19 of the plate. Here the oil drips downwardly into the first groove 9 and then if the supply of oil is great enough the oil
 30 will overflow the ridge 13 and into the groove 10 and in like manner overflow the ridge 14 into the groove 11. To ignite the oil, newspaper or similar inflammable matter is lighted and thrown onto the plate to
 35 heat the plate a sufficient amount. When the plate has been so heated, the valve 39, controlling the supply of oil through the pipe 29 is opened and oil will flow into the pre-heater and onto the plate where ignition
 40 takes place by reason of the heat in the plate, and also from the burning paper or the like which is on the plate. As the combustion continues the incoming air through the opening 15 striking against the under side
 45 of the plate will tend to cool the plate, and at the same time will in itself absorb some of the heat, thus becoming warmed and continuing upwardly against the pre-heater and then downwardly over the plate. The
 50 combustion of the hydrocarbon and air likewise heats the fuel oil within the pre-heater so that volatilization of the same and combustion is facilitated. Within the pre-heater, above the surface of the oil in the top
 55 of the pre-heater is an air chamber which is filled with warm air, which again aids in increasing the temperature of the oil within the pre-heater. The warm air within the pre-heater serves also to prevent carbonization
 60 within the pre-heater. The longer combustion takes place the greater will be the heat created, so that in a comparatively short time after starting the heater, the incoming oil is volatilized immediately on
 65 being delivered against the plate, whereupon

combustion occurs. The cap 35 is properly positioned to govern the proper supply of air to effect combustion conditions in order to utilize the greatest amount of heat from the oil. As before stated, if the weather conditions are severe and it is desired to increase the amount of heat, then the amount of oil supplied with the pre-heater may be increased by proper manipulation of the control valve whereupon a greater amount 70 of heated oil will be delivered on to the plate, with a consequent increase in the combustion in the increased amount of oil. The air drawn in through the opening 15 in the plate tends to cool the plate and also the 80 pre-heater, thus making possible continued operation of this device as a heater without fear of any damage whatsoever to any of the parts by reason of the heat of combustion. The air also tends to drive the 85 flame away from the pre-heater, thus preventing excessive heating of the pre-heater whereby carbonization of the interior of the heater is eliminated. The amount of air delivered over the surface of the plate is 90 regulated by the cap 35 and consequently proper combustion is made possible because of regulation of the air containing oxygen, in this manner.

It will be noted that my apparatus consists of but three parts, namely, the plate, the pre-heater and the air regulating cap on the pre-heater. No pilot light of any sort is required, nor any mechanical parts such as 95 motors, blowers and the like, are necessary.

I have found that my burner works satisfactorily with dark and light gas oils, with distillate, both light or medium-heavy and further it works satisfactorily with light or medium-heavy crude oil. The lighter 105 oil, such as kerosene, burns very efficiently in this device.

An advantage of my invention is that it burns inexpensive fuel oil, is quickly applied or removed, requires no moving parts of any sort, nor even a pilot light. Furthermore, it can be placed directly on the grates of a heating plant, thus making it possible in the event the burner becomes inoperative for some reason, to quickly remove the same and to build a fire of coal in the heating plant within a very short time.

While I have described more or less precisely the details of construction of my invention, yet I do not wish to be understood as limiting myself thereto, as I contemplate changes in form and proportion of parts and substitution of equivalents, as circumstances may suggest or render expedient, 115 without departing from the spirit of my invention.

I claim:

1. An oil burner including in combination, a substantially circular plate having 130

- a grooved surface and adapted to seat on the grate bars of a heater, and having a centrally disposed air opening therein, a collar defining said opening integral with said plate and extending above the uppermost part thereof, said collar having an annular ledge therearound, a pre-heater disposed above said air opening and provided with supports which rest on said ledge, said supports comprising hollow members communicating with the interior of said pre-heater and serving as outlets therefor, the upper open ends of said members being at or near the bottom of said heater, said members being adapted to discharge the contents of said pre-heater onto said plate, and means for delivering liquid fuel to said pre-heater.
2. An oil burner including in combination, a substantially circular plate having a grooved surface and adapted to seat on the grate bars of a heater, and having a centrally disposed air opening therein, a collar defining said opening integral with said plate and extending above the uppermost part thereof, said collar having an annular ledge therearound, a pre-heater disposed above said air opening and provided with supports which rest on said ledge, said supports, comprising hollow members communicating with the interior of said pre-heater and serving as outlets therefor, the upper open ends of said members being at or near the bottom of said heater, said members being adapted to discharge the contents of said pre-heater onto said plate, means for delivering liquid fuel to said pre-heater, and means for regulating the amount of air passing through said opening and for directing the same outwardly over the surface of said plate.
3. An oil burner including in combination, a circular plate having a plurality of concentrically arranged grooves on the surface thereof separated by ribs of different heights, a collar integral with said plate and centrally disposed therein defining an air opening therethrough, a ledge on the outer surface of said collar near the upper end thereof, a pre-heater above said collar supported on said ledge, outlets from said pre-heater adapted to spill the discharge therefrom downwardly onto said collar and into the grooves in the plate whereby ignition of said fuel is effected on said plate by the heat thereof, means for delivering fuel to said pre-heater, and for regulating the flow thereof, and means for regulating the flow of air through said central opening and outwardly over said plate.
4. An oil burner including in combination, a plate, a pre-heater mounted above said plate, means for directing the flow of air through said plate and against said pre-heater, means for supplying oil to said pre-heater, means for delivering oil from said pre-heater to said plate, and means on said pre-heater for regulating the flow of air over the surface of said plate.
5. An oil burner, including in combination, a plate, a pre-heater mounted above said plate, means for directing the flow of air through said plate and against said pre-heater, means for supplying oil to said pre-heater, means for delivering oil from said pre-heater to said plate, and means including an adjustable cap on said pre-heater for regulating the flow of air over the surface of said plate.

Signed at Chicago, Illinois, this 23rd day of June, 1924.

MILES J. VOTAVA.
